WINDOW SHADE FIXTURE

Solomon M. Ayoub, Ansonia, Conn.

Application October 15, 1947, Serial No. 779,988

3 Claims. (Cl. 248—262)

1

This invention relates to window shade fixtures, and more particularly to a shade-supporting fixture adapted to have clamping engagement upon a window casing.

One object of this invention is to provide a device of the above nature including clamping elements adapted to embrace the upper corners of a window casing.

Another object is to provide a device of the above nature which includes means for automatically locating the fixture in its proper position during installation, whereby no special skill will be required to install the fixtures.

Another object is to provide a device of the above nature which includes means whereby the weight of the shades and curtains will cause the clamping elements to engage the window casing more firmly.

A further object is to provide a device of the above nature which will be simple in construction, inexpensive to manufacture, easy to install and manipulate, compact, ornamental in appearance, and very efficient and durable in use.

With these and other objects in view, there have been illustrated on the accompanying drawings two forms in which the invention may conveniently be embodied in practice.

In the drawings,

Fig. 1 is a front elevation in perspective of the improved window shade fixture applied to a window casing.

Fig. 2 is a plan view of the left hand end of the same, partly in section.

Fig. 3 is a plan view of the right hand end of the same.

Fig. 4 is a fragmentary perspective view of a modification of the invention.

Referring now to the drawings in which like reference numerals denote corresponding parts throughout the several views, the letter C indicates the upper portion of a rectangular window casing having a right hand trihedral clamping jaw 10 and a left hand trihedral clamping jaw 11 in engagement with its upper corners.

The trihedral jaws 10, 11 comprise, respectively, top walls 12, 13, and end walls 14, 15, which are adapted to engage the outer edges of the casing C, and in front walls 16, 17 which are adapted to engage the face of said casing C.

The jaws 10, 11 are provided respectively with bracket arms 18, 19 extending forwardly from the inner edges of the front walls 16, 17 at right angles thereto.

The bracket arms 18, 19 are provided with circular apertures 20, 21 spaced outwardly a short

2

distance from the front walls 16, 17, in order to receive a tension means 22 whereby the trihedral clamping jaws 10 and 11 may be drawn toward each other for clamping the casing C. The tension means 22 includes a left hand rod section 23 having an end head 24 seated on the outer face of the bracket arm 19, and an end head 25 pivotally retained in one end of a turnbuckle 26.

The tension means 22 further includes a right hand rod section 27 having a threaded end 28 engaged in the turnbuckle 26 and an opposite threaded end 29 which passes through the aperture 20 of the right hand bracket arm 18 and is secured by a nut 30.

In order to support the usual window shade roller 33, the respective bracket arms 18, 19 are provided with a circular bearing aperture 31 and a slot 32 located outwardly of the tension means 22.

The front walls 16 and 17 of the trihedral jaws 10 and 11 have portions struck outwardly therefrom to form central lugs 34, 35, which will be useful for supporting a curtain rod to overlie the window shade roller 33 at substantially the same level. The top walls 12, 13 and the end walls 14, 15 of the jaws 10, 11 have portions struck inwardly to form spurs 36 upon the inside surfaces of said jaws 10, 11. Thus, the spurs 36 will engage the edge surfaces of the casing C and prevent the jaws 10 and 11 from slipping therefrom.

Operation

The improved window shade fixture may be manufactured and sold in various sizes. However, the extent of the threaded portion 28 of the rod section 27 will enable a fixture of a given size to fit any window casing within a certain range of sizes. The threaded rod portion 29 offers a further means of adjustment. In use, the clamping jaws 10 and 11 will be placed upon the upper outer corners of the window casing C and the turnbuckle 26 rotated in order to place the jaws under tension.

The end walls 14, 15 will thereby be drawn into tight clamping engagement with the outer edge surfaces of the casing C—the spurs 36 thereon entering into said casing to prevent slipping of the fixture.

In the process of installing the fixture, the spurs 36 and the top walls 12, 13 will normally engage the top edge surface of the casing C sufficiently to prevent sliding of the top walls 12, 13 upon the casing. However, if an especially firm engagement is desired, the jaws 10, 11 may be

pressed downwardly during the installing operation in order to cause the spurs 36 to engage in the casing C to their full extent.

After the turnbuckle 26 has been tightened, the fixture will then be ready to receive a window shade roller 33 in the aperture 31 and slot 32 of the bracket arms 18, 19. If desired, a curtain rod may then be applied to the lugs 34, 35.

Modified form

In the modified form shown in Fig. 4, provision is made of a pair of trihedral clamping jaws having substantially the same structure and function as the jaws 10, 11 in the first form of the invention. The right-hand jaw of the modified form is indicated at 37. In this form, however, the jaw 37 is provided with an elongated slot 38 which is adapted to secure a T-head 39 formed on the end of a flat strip 40 of a modified tension means.

A flat strip 41 is provided which has identical securing with a similar jaw at the other side of the casing. The strips 40, 41 are connected by means of an intermediate strip 42 which is provided with a reduced hook end 43 adapted to engage selectively in one of a longitudinal series of apertures 44 in the flat strip 41. The strips 40 and 42 normally overlap in their installed position, and are provided with end eyes 45, 46, respectively, connected by a toggle arm 47 having angular end portions 48, 49 received in the eyes 45, 46.

The end portion 48 is continued in a plane parallel to the toggle arm 47 in the form of an angular locking rod 50 having an upturned end 51 adapted to be engaged behind the flat strip 40. The end portion 49 of the toggle arm 47 has a hooked continuation 52 over which the locking rod 50 is adapted to be engaged in order to retain the toggle arm 47 in a locked position.

Operation of modified form

The modified form will be installed in a manner similar to the first form of the invention, with the exception of the tension means. In this form the T-head 39 will be entered through the elongated slot 38, and then rotated 90 degrees in order to prevent its withdrawal. The jaws 37 having first been applied to the corners of the window casing, the hooked end 43 of the connecting strip 42 will then be entered through the appropriate aperture 44 and the toggle arm 47 swung to its locked position, in which the strips 40 and 42 overlap, as shown in Fig. 4.

The upturned end 51 of the locking rod 50 will then be snapped behind the strip 40 and the locking rod 50 engaged in the hook 52, whereby the toggle will be firmly secured.

One advantage of the instant invention is that the shape of the trihedral jaws 10 and 11 furnishes a means whereby a fixture may be quickly and accurately located upon the casing, thus avoiding the necessity for measuring or otherwise carefully determining the points at which the fixture should be applied.

Another advantage is that the device is of simple construction, and includes a minimum of projecting parts. The face of the window casing will not be mutilated or marred in any way, and if it is desired at any time to remove the fixture, the face of the casing will bear no evidence of the installation.

Another advantage is that the spurs 36 will effectively resist displacement of the clamping jaws from the window casing. Excessive tension, as might be caused by tightening the turnbuckle 26 more than necessary, will not cause the clamping jaws to slip from the casing.

Further, the spurs 36 in the top walls 12, 13 will retain the jaws upon the casing even though excessive weight is applied to the bracket arms 18, 19, or to the lugs 34, 35. In fact, an increase in the load upon the fixture will only result in a firmer engagement of the spurs with the edge surfaces of the window casing.

No noticeable marks will be left by the spurs 36 inasmuch as they are of thin construction and disposed to lie with the grain of the wood. However, the spurs in the end walls 14, 15 may be omitted, if desired, in which case, the only marks left upon the casing will be on its upper edge and inconspicuous.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a window shade fixture, a pair of brackets each comprising a trihedral clamping jaw including a front wall and a bracket arm extending outwardly from said front wall, tension means connecting said brackets, said tension means comprising a pair of sections each connected to one of said brackets, and a toggle device for drawing the sections of said tension means toward each other for clamping said brackets in engagement with a window casing.
2. The invention as defined in claim 1, in which said tension means is provided with a T-shaped end detachably engaged in an elongated slot in one of said bracket arms, whereby said bracket may be quickly attached to and detached from said tension means.
3. The invention as defined in claim 1, in which one of said pair of sections comprises a strip having a longitudinal series of apertures therein, and a hooked strip adapted to engage selectively in any one of said apertures, whereby the length of said tension means may be adjusted to permit operation of the toggle means when the fixture is applied to window casings of different widths.
